UNITED STATES PATENT OFFICE.

STANLY LECZYCKI, OF DETROIT, MICHIGAN.

LOCK.

Application filed May 12, 1921. Serial No. 468,811.

To all whom it may concern:

Be it known that I, STANLY LECZYCKI, a citizen of Poland, residing at Detroit, in the county of Wayne and State of Michigan, have invented certain new and useful Improvements in Locks, of which the following is a specification.

This invention relates to improvements in locks and more particularly to that class of locks used for securing doors in closed position. The principal object of the present invention resides in the provision of a dead-locking means for rendering the lock inoperative until released.

Another object of the invention is to provide a latch adapted to be housed in the same casing with the lock so that both may be handled as a unit.

With these and other objects in view the invention consists in the novel construction, combination and arrangement of parts which will be fully set forth in the following specification, claimed and illustrated in the accompanying drawing, in which,

Figure 1 is an end view of this combined lock and latch,

Figure 2 is a side view of Figure 1,

Figure 3 is a sectional view through line 3-3 of Figure 4,

Figure 4 is a side view of the device showing the cover plate removed, and

Figure 5 is a detail perspective of the deadlock releasing key.

Referring to the drawings by characters of reference the numeral 10 designates the lock casing having a cover plate 11 which is secured to the edges of the flanges 12 formed on the marginal edges of the plate 13. Formed at proper intervals on the inner side of the plate 13 within the confines of the flanges 12 are inwardly extending lugs 14-15 and 16.

Formed in the plates 13 and 11 are alined openings for the reception of a barrel member 17 having formed therein a longitudinally extending rectangular opening 18 for the reception of the usual rectangular shaft to which the customary knobs are secured. Formed adjacent one end of said barrel member is a rock arm 19, the flat face of which engages a rocker 20 which is pivoted at its upper end as at 21 behind a tongue 22 formed on the inner side of the uppermost flange 12 adjacent its rear end. A tongue 23 extends forwardly from the upper end of the rocker upon the under side of which

bears the end of a leaf spring 24, the opposite end of which is secured between the lug 14 and a downwardly extending shoulder 25 formed at the extreme forward end of the upper flange 12. Pivoted connected as at 26 to the lower end of the rocker 20 is the rear end of a latch member 27, the forward end of which is slidably mounted in an opening formed in the forward cover plate 28. It will thus be seen that the spring 24 will yieldably hold the latch projected and that upon turning the barrel 17 the latch may be withdrawn against the pressure of said spring.

Slidably mounted between the lugs 15 and 16 is the locking bolt 29, the forward end of which projects through an opening formed in plate 28 directly beneath the opening through which the latch member operates. As shown in the drawings the lower edge of the bolt 29 is provided with a longitudinal recess, the end walls of which cooperate with the lug 15 to limit the movement of said bolt. Formed near the inner end of said bolt and extending thereinto from its under side is a recess, the end walls of which are arcuately formed to provide cam faces 30 and 31 which are engaged by the bit of a key which is adapted to be entered into the lock through keyholes 32 formed near the lower rear end of the plates 11 and 13. The upper edge of the bolt 29 is formed near its rear end with a stop lug 33, the use of which will be more fully hereinafter described.

Pivoted as at 34 to the plate 13 and extending rearwardly in parallel relation to the locking bolt is a lever 35 formed near its rear end with an upstanding arm provided at its upper end with an angularly extending tongue 36 which is adapted to rest upon the upper edge of the bolt and provide a stop for the lug 33. A spring 37 is mounted in a suitable bracket 38 and its rear end bears on the upper side of the tongue 36 to hold the same in frictional contact with the upper edge of the bolt and in the path of the lug 33. As shown in the drawings the lower edge of the lever 35 lies in the path of the bit of the key so that when the said key is turned in the lock, the lever will be swung upwardly about the pivot 34 so as to elevate the tongue 36 in such position as to clear the lug 33 so that the bolt may be projected or withdrawn according to its original position.

In order to provide a dead lock for the bolt 29, a pin 39 projects inwardly from the plate 13 at a point slightly above the free end of the spring 37 and pivotally mounted on said pin is a barrel 40 provided with a flattened face 41. An arm projects angularly from the barrel 40 near one end and is provided with an angular extension 42; the under face of which is adapted to be moved into contact with the upper side of the spring 37 adjacent its free end to prevent said spring and its associated mechanism from moving upwardly and releasing the bolt.

The position of the angular extension 42 is controlled by a key 43 provided with a tubular barrel 44 provided interiorly with a flattened portion 45 which is adapted to coincide with the flattened face 41 of the barrel 40. It will be understood that the plate 11 is provided with an opening 46 through which the tubular barrel 44 of the key 43 may be entered into the lock.

While in the foregoing there has been shown and described the preferred form of this invention it is to be understood that

minor changes in the details of construction, combination and arrangement of parts may be made without departing from the spirit and scope of the invention as claimed. 30

What is claimed is:—

A lock comprising a casing, a bolt slidable in said casing, said bolt being adapted to be projected and retracted by a key, a stop lug on the upper edge of the bolt, a lever pivoted within the casing, a tongue projecting laterally from the upper edge of the lever in position to engage the lug, when the bolt is in projected or retracted position, a flat leaf spring normally urging the tongue against the upper edge of the bolt, said tongue being elevated out of contact with the bolt by the bit of the bolt actuating key, and a key actuated member mounted above the tongue, and adapted to be turned 45 into engagement with the spring directly over the tongue to prevent said tongue from being moved out of the path of the stop lug.

In witness whereof I affix my signature. 50

STANLY LECZYCKI.
